SPREAD SHEET

Herbert C. Davis, Bronxville, N. Y., assignor to
 The McBee Company, Athens, Ohio, a corporation

Application March 11, 1949, Serial No. 80,846

2 Claims. (Cl. 281—21)

1

This invention relates to a spread sheet.

It is an object of the invention to provide a spread sheet comprising a plurality of interlocked, telescoping component sheets (which may be printed and/or ruled as desired and upon which information of any desired sort may be placed), such spread sheets being of simple construction and easy to assemble.

It is a further object of the invention to provide a spread sheet component which is easily fabricated and which involves no wastage of material in its fabrication.

These and other objects of the invention will be apparent from the ensuing description and the appended claims.

One form which the invention may assume is exemplified in the following description and illustrated by way of example in the accompanying drawings, in which:

Fig. 1 is a plan view of the component sheet of the spread sheet of the invention.

Fig. 2 is a plan view of the spread sheet itself.

Referring now to the drawings, the component sheet is designated as 10 and the spread sheet, comprising an assembly of component sheets 10, is designated as 11. The component sheet is illustrated as being rectangular in shape and as being scored at 12 to provide a flap 13 which may be folded back against the body portion 14 of the component sheet. The flap 13 is cut parallel to the end of the sheet to provide a slit 15 for a purpose described hereinafter. The body portion 14 of the component sheet is cut adjacent the score line 12 to provide a transverse slit 16 and two longitudinal slits 17. A tab 18 is thus formed.

In assembling the component sheets thus described, the flap 13 of each component sheet is folded back against the rear surface of the body portion 14, and the tab 18 of each sheet 10 (except the upper one) is inserted in the slit 15 of the next overlying sheet. A tape 19, such as Scotch tape or any other suitable adhesive-coated tape, is applied to the tab in the manner illustrated in Fig. 2 so as to lock the tab 18 in the companion slit 15. Each tab 18 is free to shift in its slit 15, thus allowing spreading of the sheet in the manner illustrated in Fig. 2. When so desired, the component sheets may be telescoped into compact form, as for storage.

It is thus apparent that a spread sheet and a component sheet therefor have been provided which fulfill the objects hereinabove stated. Thus, the only operations necessary in fabrication of the component sheet, other than cutting out a blank of the proper shape and size, are the

5 following: The score line 12 is formed and the sheet is cut at only two places. The only operations involved in assembling the sheets consist of folding the flaps 13, inserting the tab 18 in the slits 15 and applying the tape 19.

While I have shown the preferred form of my invention, it is to be understood that various changes may be made in its construction by those skilled in the art without departing from the 10 spirit of the invention as defined in the appended claims.

Having thus described my invention, what I claim and desire to secure by Letters Patent is:

15 1. A spread sheet component comprising a sheet having a flap formed at one end foldable about a line generally parallel to said end, said flap having a single slit formed therein parallel to said end and the body portion of said sheet below said flap having a single tab formed therein which is receivable and slidable in the slit of a companion component sheet, the distance of the slit to the edge of said one end of the sheet being less than the dimension of the tab taken in the same direction, whereby the tab may be inserted 20 through the slit of a companion component sheet to extend across the sheet material located between the slit and the adjacent end edge of the component sheet.

25 2. A spread sheet comprising a plurality of component sheets, each having a flap at one end folded about a line generally parallel to said end, a single slit formed in said flap and a single tab formed in the body portion of said sheet adjacent said fold line, the tab of one component being 30 inserted and slidable in the slit of another component, the slit in each component sheet being substantially longer than the dimension of the tab slidable therein taken in the same direction, the slit in each component sheet being spaced 35 from the edge of said one end thereof a distance less than the dimension of the tab slidable therein taken in the same direction, and an adhesive-coated tape applied to the free end of each 40 inserted tab and to the body portion of its component sheet to lock the tab in its companion slit.
